UNITED STATES PATENT OFFICE.

JULIUS MALTBY AND THEODORE H. MILLER, OF WATERBURY, CONNECTICUT, AS
SIGNORS TO WATERBURY BUCKLE CO., OF WATERBURY, CONNECTICUT, A COR-
PORATION.

GAEMENT-FASTENER BUTTON.

Application filed February 6, 1923. Serial No. 617,257.

To all whom it may concern:

Be it known that we, JULIUS MALTBY and THEODORE H. MILLER, citizens of the United States, residing at Waterbury, in the county of New Haven and State of Connecticut, have invented a new and useful Improvement in Garment-Fastener Buttons; and we do hereby declare the following, when taken in connection with the accompanying drawings and the characters of reference marked thereon, to be a full, clear, and exact description of the same, and which said drawings constitute part of this application, and represent, in—

Fig. 1 a plan view of one form which our improved garment-fastener button may assume.

Fig. 2 a view thereof in longitudinal, central section on the line 2—2 of Fig. 1.

Fig. 3 a detached, edge view of the button-base.

Fig. 4 a view corresponding to Fig. 2, but showing the button-head as subjected to the action of a die for bending down the embedded prongs into their clinching positions.

Fig. 5 a plan view of still another form which our invention may assume.

Fig. 6 a view thereof in central, transverse section on the line 6—6 of Fig. 5.

Our invention relates to an improvement in garment-fastener buttons, such as are used in garter-clasps, stocking and hose supporters, and kindred articles, the object being to produce, at a low cost, an article of superior strength, durability and appearance, constructed with particular reference to positively preventing the rubber button-head from being wrenched away from its sheet-metal base.

With these ends in view, our invention consists in a garment-fastener button having certain details of construction as will be hereinafter described and pointed out in the claims.

In carrying out our invention, as shown in Figs. 1 to 3 inclusive, we employ a one-piece, sheet-metal button-base, oblong in general form and consisting, as it were, of two lobes 10, each having a segmental, threading-opening 11, and centrally united upon their straight, inner edges by an integral, transverse web 12, from the opposite edges of which rise integral anchoring-prongs

13, produced by cutting and bending the metal lying between the said lobes 10 and the outer ends thereof inward to the said transverse web. With the upper ends of these prongs slightly bent away from each other, as shown in Fig. 3, a shanked rubber button-head 14 is driven over them, as shown in Fig. 2. After the button-head has been driven home over the prongs, its outer face is subjected to the action of a suitable die 31, as shown in Fig. 4, or otherwise subjected to pressure in such a manner that the button being of resilient material the ends of the prongs are bent outward and downward to form clinching-fingers 15, as shown in full lines in Figs. 2 and 4, whereby the button-head is positively secured to the button-base against being wrenched away therefrom. When the pressure of the die 31 is removed from the button-head 14, the same, being resilient, resumes its normal shape, as shown in Fig. 2, with the production of pockets or voids 32 directly adjacent to the outer faces of the prongs 15, but these pockets or voids in nowise affect the operation of the completed button, impair its strength, or mar its appearance. Or, the ends of the prongs might be bent inward, toward each other, to form clinching-fingers for positively securing the button-head to the button-base, but preferably they are bent outward, away from each other, as shown.

In the modified construction shown by Figs. 5 and 6 of the drawings, the button-base consists of two independent, segmental lobes 25, each having a segmental threading-opening 26 and each provided, upon its inner edge, with an integral, upstanding prong 27, over which the rubber button-head 29 is driven, after which the prongs are bent outward to form clinching-fingers 30, whereby the two lobes are united, and the button-head positively secured to the two-part button-base.

We would, therefore, have it understood that we do not limit ourselves to the exact construction shown and described, our invention comprehending the positive fastening of a rubber button-head to a button-base, by means of prongs, the ends of which are sufficiently bent within the button-head to form clinching-fingers for firmly anchoring the same to the base, whether the ends are bent outwardly or inwardly.

2
We claim:

1. A garment-fastener button, having a button-base provided with two upstanding prongs, and a solid button-head of resilient material in which the said prongs are driven and embedded for the anchorage of the head to the base, the ends of the said prongs being bent within the outer face of the said solid head for anchoring the head to the base.
2. A garment-fastener button, having a button-base provided with two upstanding prongs, and a solid rubber button-head into which the said prongs are driven and em-

bedded for the anchorage of the button-head to the base, the outer ends of the said prongs being bent in opposite directions within the outer face of the said solid button-head for securing the same to the base.

In testimony whereof, we have signed this specification in the presence of two subscribing witnesses.

JULIUS MALTBY.
THEODORE H. MILLER.
